UNITED STATES PATENT OFFICE.

LEONARD VANTREPOTTE, OF MULBERRY, KANSAS.

ENVELOPE.

Application filed March 30, 1925. Serial No. 19,438.

This invention relates to an improved mailing envelope and seeks, among other objects, to provide a device of this character embodying a shield for protecting the contents of the envelope against injury by an envelope opener or the like when the envelope is being opened.

The invention seeks, as a further object, to provide an envelope embodying a shield in the form of an auxiliary flap at the mouth of the envelope and so disposed that said flap may be readily folded into the envelope over the letter preparatory to the sealing of the envelope.

Another object of the invention is to so dispose the auxiliary flap that after the envelope is sealed, said flap will form a second thickness at the upper longitudinal edge of the envelope so that the operator, when attempting to open the envelope will, upon finding the two thicknesses of the auxiliary flap and the closure flap of the envelope difficult to sever, choose the single thickness of the envelope flap with the result that injury to the letter will be avoided.

And the invention seeks, as a still further object, to provide the auxiliary flap with means whereby said flap may be readily pulled from its folded position within the envelope to permit the ready removal of the letter.

Other and incidental objects will appear hereinafter.

In the accompanying drawings:

Figure 1 is a rear elevation of my improved envelope.

Figure 2 is a sectional view on the line 2-2 of Figure 1, looking in the direction indicated by the arrows.

In accordance with the present invention, the improved envelope is preferably formed from a blank of suitable paper and includes an oblong body 10 having a one-piece front portion 11, and a back portion 12 which is formed of end flaps 13 and an overlapping bottom flap 14 adhesively secured to the adjacent margins of the end flaps. The front portion 11 is continued to form a closure flap 15 provided at its free longitudinal margin with a band of adhesive 16 so that said flap may be secured in folded position to the back portion 12 over the mouth of the body for closing the envelope, while the back portion 12 is provided with a downwardly curving free edge to permit the ready removal of the contents of the envelope after the

flap 15 has been severed along its folded edge.

Mounted within the mouth of the body 10 is a shield which, as best shown in Figure 1, is in the form of an auxiliary flap 17. Near its base edge, the flap is folded to form an attaching strip 18 which is adhesively secured to the front portion 11 of the body at the base of the closure flap 15 so that the flap 17 is thus securely attached and is, furthermore, provided with a crease at the upper edge of said strip so that after a letter has been placed within the body, the flap may be readily folded downwardly over the letter to project within the back portion 12. As will be observed, the free edge of the flap 17 is preferably curved to conform to the curvature of the upper edge of the back portion 12 of the body and is of a width to uniformly overlap said back portion at its upper margin. Adhesively secured at its lower end to the auxiliary flap is a tab 19 arranged medially of said flap, and preferably attached near the free edge thereof. The tab is free at its upper end so that said tab may be readily grasped and is formed of a piece of thin paper or, in other words, of a paper considerably thinner than the paper of which the envelope is formed. Thus, the presence of the tab will not be noticeable when the envelope is sealed.

After the letter has been placed in the envelope, the flap is, as shown in Figure 2, folded downwardly over the letter to extend beneath the back portion 12 of the body when the flap 15 is sealed in the usual way for closing the envelope. Thus, when an envelope opener or the like is inserted beneath the flap 15 and operated to sever said flap at the upper longitudinal edge of the envelope, the flap 17 will serve to protect the letter against injury by the opener. After the flap 15 is severed, the free end of the tab 19 may be grasped for pulling the flap 17 upwardly to open position and exposing the letter. Should the envelope opener be inserted beneath both flaps, when starting to open the envelope, the double thickness presented by said flaps at the upper longitudinal edge of the envelope will be found relatively hard to sever with the result that the attention of the operator will be directed to the presence of the auxiliary flap 17 and a fresh start made by inserting the opener beneath the flap 15 only. I accordingly provide an envelope wherein likelihood of in-

jury to the letter incident to the opening of the envelope will be materially lessened.

Having thus described the invention, what I claim is:

- 5 An envelope comprising a body portion having a front wall and a rear wall joined at its bottom and sides to said front wall and together with the front wall forming a pocket open at its top, the upper edge of
- 10 said rear wall being disposed below the upper edge of said front wall, a guard flap secured against the inner face of said front wall along its upper edge portion and adapted to be tucked into the pocket with its

lower edge portion overlapped by said rear wall, a tab secured at its lower end to the outer face of said guard flap above the upper edge of said rear wall and extending upwardly with its upper end terminating short of the upper edge of the guard flap, said tab being of not greater thickness than the rear wall, and a closure flap extending from the upper edge of said front wall and adapted to be secured upon the outer face of said rear wall and close the upper end of the 25 pocket.

In testimony whereof I affix my signature.

LEONARD VANTREPOTTE. [L. s.]
